OSCILLATORY TEASING COMB
Anthony Paccione, 1681 65th St.,
Brooklyn, N.Y. 11220
Filed Mar. 25, 1965, Ser. No. 442,719
4 Claims. (Cl. 132—11)

ABSTRACT OF THE DISCLOSURE

An oscillatory teasing comb comprising a housing having an annular portion at one end and a flat and open longitudinal portion extending for substantially the length of a comb and terminating in a raised portion. Means are provided for pivotally mounting the frame in the housing on the inner face thereof in order to permit an oscillating movement of the frame in the housing. A drive shaft is rotatably mounted relative to the housing having eccentric means on the drive shaft, and means for automatically selectively oscillating the drive shaft are provided, as well as a plate operatively connecting the drive shaft with the frame for oscillating movement of the latter, and a teasing comb removably secured in the frame and joining the oscillating movement of the latter.

The present invention relates to an oscillatory teasing comb and more particularly to mechanism for imparting oscillatory motion to teasing combs.

Teasing combs are known which have to be manually operated, in order to bring about the teasing of human hair.

It is desirable that the motion of the teasing comb is oscillatory for a predetermined limited angle.

It is, therefore, one object of the present invention to provide an oscillatory teasing comb, which comprises a frame wherein the teasing comb is removably mounted and the frame itself is pivotally mounted in an open housing for an oscillatory movement such that the plane of the teasing comb oscillates about an axis extending through the back of the teasing comb.

It is another object of the present invention to provide an oscillatory comb which includes means for imparting an oscillatory movement to the comb about an axis extending through the back of the comb.

With these and other objects in view, which will become apparent in the following detailed description, the present invention will be clearly understood in connection with the accompanying drawing, in which:

FIGURE 1 is a top plan view of the oscillatory teasing comb including a housing receiving the comb;

FIG. 2 is an axial section of the housing receiving the teasing comb;

FIG. 3 is a section along the lines 3—3 of FIG. 2;

FIG. 4 is a section along the lines 4—4 of FIG. 2; and

FIG. 5 is a section similar to that of FIG. 4 disclosing another embodiment of the teasing comb.

Referring now to the drawing, and in particular to FIGS. 1 to 4, the oscillatory teasing comb comprises a main housing 1 which is preferably formed as a cylindrical hollow body open at one end and having an outer thread 2 which receives a cap member 3 having a complementary inner thread 4, whereby the cap member 3 is easily removed.

An electric battery 5 is disposed in the housing 1 adjacent an electric motor 6 fed by the battery 5 and having a shaft 7 which extends through an opening 8 provided in the end wall 9 of the housing 1.

An extension 10 of the housing 1 is secured to the latter and comprises an annular member 11 from which a flat open housing portion 12 extends integrally. The

2

annular member 11 surrounds the end portion of the housing 1 and is secured thereto by means of screws 13. The flat open housing portion 12 has at its free end an upwardly bent portion 14.

5 A frame 15 of substantially U-shape is disposed in the flat open housing portion 12 and is equipped with pivot pins 16 projecting outwardly from the leg members of the U-shaped frame 15, while the base of the latter has an outer bottom face of circular cross-section and is received in a recess 17 of complementary circular cross-section of the flat open housing portion 12. The pivot pins 16 are mounted in complementary recesses of the end wall 9 of the housing 1 and of the upwardly directed portion of the housing portion 12, respectively, so that the frame 15 is mounted by means of the pins 16 to perform an oscillatory movement. The base of the U-shaped frame 15 has preferably two clamps 18 extending upwardly and receiving removably a teasing comb 19, so that the latter can be easily removed for replacement or for cleaning purposes.

10 The teasing comb 19 disclosed in FIGS. 1 and 4 has three parallel rows on teeth 20, while another embodiment of the teasing comb 19' disclosed in FIG. 5, has a single row of teeth 20'. It is to be understood that 15 teasing combs can be provided which have any desirable number of rows of teeth.

15 The motor shaft 7 has secured thereto at its free end a disc 21 which is equipped with a pin 22 extending eccentrically and perpendicularly therefrom. A longitudinal plate 23 is provided adjacent to and outside of the end wall 9 of the housing 1, which plate 23 has a bore through which one of the pins 16 extends and at its upper end is equipped with a longitudinal slot 24 which receives the eccentrically disposed pin 22. The lower end 20 of the plate has a bent over portion 25 which is received in the opposite outer face of the base of the frame 15.

20 The housing 1 is equipped with a longitudinal slot 26 in which a switch member 27 is received for movement in axial direction of the housing for opening and closing the motor circuit in conventional manner. A spring 28 urges the battery 5 to the motor 6 to provide proper contact therebetween.

25 Upon rotation of the motor 6 by setting the switch 27, the pin 22 will confer an oscillatory motion to the plate 23 and the latter transmits this oscillating motion to the frame 15 about the axis defined by the pins 16. In this manner, due to the mounting of the teasing comb 19 in the frame 15, the teasing comb 19 will be likewise subjected to an oscillating motion.

30 While I have disclosed two embodiments of the present invention, it is to be understood that these embodiments are given by example only and not in a limiting sense, the scope of the present invention being determined by the objects and the claims.

35 I claim:

1. An oscillatory teasing comb comprising
a housing having an annular portion at one end and
a flat and open longitudinal portion extending for
substantially the length of a comb and terminating
in a raised portion,
said flat and open portion having an inner face of
circular arc cross-section,
a substantially U-shaped frame having a base and two
leg members,
the outer face of said base having a circular arc cross-
section complementary to that of said inner face
of said flat and open portion of said housing,
means for pivotally mounting said frame in said hous-
ing on said inner face thereof in order to permit
an oscillating movement of said frame in said hous-
ing,

a drive shaft rotatably mounted relative to said housing,
eccentric means on said drive shaft,
means for automatically selectively oscillating said
drive shaft,
a plate operatively connecting said drive shaft with said
frame for oscillating movement of the latter, and
a teasing comb removably secured in said frame and
joining the oscillating movement of the latter.
2. The teasing comb, as set forth in claim 1, wherein
said means for pivotally mounting said frame in said
housing comprises pins extending laterally from said
legs in said frame and being mounted in said housing.
3. The teasing comb, as set forth in claim 1, which
includes
an additional substantially cylindrical housing secured
to said annular portion,
said automatic means comprising,
an electric battery and an electric motor disposed
axially relative to each other in said cylindrical
housing,
circuit means for opening and closing, respec-
tively, the circuit to said motor, and
said motor including said drive shaft.
4. An oscillatory teasing comb comprising
a housing having an annular portion at one end and
a flat and open longitudinal portion extending for
substantially the length of a comb to terminate in
a raised portion,
said flat and open portion having an inner face of
circular cross-section,
a U-shaped frame having a base and two leg members,
the outer face of said base having a circular cross-

5

15

25

30

section complementary to that of said inner face
of said flat and open portion of said housing,
means for pivotally mounting said frame in said hous-
ing in order to permit an oscillating movement of
said frame in said housing,
a drive shaft,
eccentric means on said drive shaft,
a plate operatively connecting said drive shaft with
said frame for oscillating movement of the latter,
and
a teasing comb removably secured in said frame and
joining the oscillating movement of the latter,
said eccentric means on said drive shaft comprises a
disc secured to said drive shaft and having a pin
eccentrically mounted thereon,
a longitudinal plate having a longitudinal slot at one
end thereof, in order to receive said eccentrically
mounted pin, and
said longitudinal plate has at its other end a bent over
portion received by the opposite leg member of said
frame, said eccentrically mounted pin and said bent
over portion of said plate being disposed on opposite
sides of the pivotal axis of said frame.
